INSIDE DOOR LOCK

Hans Berger, 17647 Belinda St., Encino, Calif.
Filed Dec. 4, 1964, Ser. No. 416,095
7 Claims. (Cl. 292—67)

This application is a continuation-in-part of my application Serial No. 364,428 filed May 4, 1964.

This invention relates to a door lock for use on the inside of a door, to provide security and safety for the occupants of a house or room.

Almost all locks, latches and fastening devices which are now in use on the inside of a door have the disadvantage that they can be forced open or torn loose through the application of extreme force to the door from the outside.

It is the primary object of my invention to provide an inside door lock which is so constructed that it is impossible for it to be opened or torn loose, regardless of how much force is applied to the outside of the door.

Another object of my invention is to provide a lock of the type described which can be mounted on any door or door jamb without requiring any alteration in the door structure other than possibly mortising the lock parts slightly into the side of the door and/or door jamb, wherever this is required.

A further object of my invention is to provide a lock of the class described which is extremely simple and economical to manufacture, so that it can be sold at a relatively low price for widespread distribution and sale. In particular, two of the principal parts forming my lock are substantially identical with each other, so that they can be formed from a single blank.

Still another object of the invention is to provide an inside security door lock which can be mounted on either a left or right hand opening door.

Another object of my invention is to provide a lock of the type described in which an auxiliary latch operable only from the inside acts to hold the latch member in place and prevent it from being opened from the outside by the insertion of a burglary tool between the door and door jamb.

In essence, my invention contemplates an inside door lock which includes a pair of side plates, one of which is adapted to be mounted on the inside edge of the door and the other of which is adapted to be mounted in a corresponding position on the side edge of the door jamb. Each of the side plates is provided with a portion which protrudes inwardly into the room. The protruding portion of each side plate is provided with a substantially vertically directed slot.

A latch member is preferably pivotally mounted on one of the side plates so that it may be pivoted between open and closed positions and be securely held in each such position by the force of gravity. When the latch member is disposed in its closed position, it has a portion which fits within the slots to prevent the movement of either side plate with respect to the other, thus preventing the door from being opened.

The fastening members which secure the side plates to the door and door jamb are preferably directed transversely to the door and door jamb, so that they cannot possibly be pulled out when the door is closed, regardless of the amount of force which is applied to the outside of the door.

My invention also comprises such other objects, advantages and capabilities as will later more fully appear and which are inherently possessed by my invention.

While I have shown in the accompanying drawings preferred embodiments of my invention, it should be understood that the same are susceptible of modification and

2

change without departing from the spirit of my invention.

Referring to the drawings:

FIG. 1 is a perspective view of a portion of a door and door jamb showing my lock mounted thereon, with the door and lock both disposed in open position;

FIG. 2 is a perspective view of a portion of a door and door jamb in closed position, with the lock and auxiliary latch also in closed position, the door jamb being disposed on the opposite side from FIG. 1 and the lock being modified accordingly;

FIG. 3 is a top plan view of the structure shown in FIG. 1, with the door, lock and auxiliary latch in closed position;

FIG. 4 is a sectional view taken along line 4—4 of FIG. 3, showing the auxiliary latch assembly.

A preferred embodiment which has been selected to illustrate my invention comprises a side plate 10 having an inner portion 11, which is adapted to be mounted in an overlying relationship to the side edge of a door jamb. A fastening member such as a screw 13 extends through an opening in the center of the inner portion 11 into the door jamb. The portion of the face of the side plate 10 immediately surrounding the screw opening may be counter-sunk so that the head of the screw 13 is flush with the face of the side plate 10.

The outer portion 17 of the side plate 10 protrudes toward the inside of the room. It carries a vertically directed straight slot 15, which extends downwardly from its top edge. The side plate 10 may be mortised as shown in the drawings, or mortising may be omitted if there is sufficient clearance between the door and door jamb to accommodate the side plates.

A second side plate 18 is formed in substantially the same manner as the side plate 10. It includes an inner portion 19, which overlies the side edge of the door in a position corresponding to and aligned with the inner portion 11 of the side plate 10. A screw 21 extends into the door. The side plate 18 may be mortised as shown, or the mortising may be omitted if it is unnecessary. The outer portion 22 of the side plate 18 carries a vertically directed straight slot 23 which corresponds to and is aligned with the corresponding slot 15 of the side plate 10.

45 A latch member 26 is mounted on the outer portion 22 or the outer portion 17 by means of a rivet 27, which is mounted in an opening 32. The latch member 26 comprises a pair of sides 28 and 29, which extend substantially parallel to the side plates 10 and 18 when the latch member 26 is in closed position. The sides 28 and 29 are joined by an integral flat catch 31.

Each of the sides 28 and 29 of the latch member 26 is provided with an elongated slot 24, which is adapted to fit around the rivet 27. The rivet 27 may be mounted on either side 28 or 29 for use of the lock on either a left or right hand door. The latch member 26 is accordingly free to rotate on the rivet 27 and is also capable of limited vertical movement with respect to the side plate upon which it is mounted.

50 60 The latch member 26 is movable between two positions, both over center with respect to the pivot point (rivet 27), so that gravity tends to retain the latch member 26 in position.

65 FIG. 1 of the drawings shows the latch member 26 in its retracted or open position, in which the latch member is suspended beneath the side plate 18.

70 FIGS. 2—4 of the drawings show the latch member 26 in its closed or locked position, in which the catch 31 is directed vertically and is disposed within the aligned slots 15 and 23 of the side plates 10 and 18. The latch member 26 is rotated clockwise from the position shown in

FIG. 1 to a position wherein the catch 31 is disposed above the slots 15 and 23 in the side plates. The slot 24 then permits the latch member 26 to move vertically downwardly so that the catch 31 is disposed within the slots 15 and 23, as shown in FIGS. 2-4 of the drawings.

It will be noted that when the latch member 26 is in locked position and the catch 31 is disposed within the slots 15 and 23, it is impossible for either of the side plates 10 and 18 to be moved with respect to the other and it is accordingly impossible for the door to be opened. If the door is moved toward open position, the catch 31 engages the edge of the stationary slot 15, to prevent further opening movement of the door.

It will also be noted that the screws 13 and 21 are directed transversely to the side plates 10 and 18 and are so disposed that they cannot be pulled out by the exertion of force upon the door, because there is insufficient space between the door and door jamb to permit them to be pulled out.

The latch member 26 should always be mounted on the door rather than the door jamb. My lock may be changed for use on a left hand or right hand opening door by merely changing the latch member 26 from one side plate to the other. All of the parts remain the same.

It should be noted that when the latch member 26 is in closed position, the sides 28 and 29 enclose and are disposed in close parallel relationship to the outer portions 17 and 22 of the side plates 10 and 18. They thus act to prevent any lateral movement or separation of the outer portions 17 and 22 in a direction away from each other which might result in permitting the door to be opened.

In order to prevent the latch member 26 from being released by the insertion of a thin burglary tool between the door and door jamb from the outside, I provide an auxiliary latch 33. The auxiliary latch 33 has adjacent its midportion a short elongated slot 34 which fits around the rivet 27 to mount the auxiliary latch 33 for pivotal movement and also for limited vertical movement.

The upper end of the latch 33 is provided with a hook 35, which is adapted to fit around a pin 36, which is provided on each side 28 and 29 of the latch member 26. The slot 34 permits the necessary limited vertical movement when the hook 35 is moved to and from engagement with the pin 36.

The auxiliary latch 33 may, of course, be omitted without affecting the operation of the remainder of the device. It may also be left open by the user, if desired.

The outer portions 17 and 22 of the side plates 10 and 18 and the sides 28 and 29 of the latch member 26 may be provided with openings which are aligned when the latch member 26 is in locked position. Such openings may accommodate a padlock, bolt or other locking means to hold the latch member 26 in closed position.

I claim:

1. An inside door lock comprising a pair of side plates adapted to be mounted in corresponding positions on the side edges of a door and door jamb, each of said side plates having an inner portion secured in overlying relationship to the door or door jamb by a fastening member which extends transversely to said side plate and door or door jamb, each of said side plates having an outer portion protruding from the door or door jamb, the outer portion of each of said side plates having a vertically directed straight slot, said slots being aligned with each other when the door is closed, a latch member slidably and pivotally mounted on the outer portion of the side plate carried by the door, said latch member having a straight catch adapted to fit within said slots, said latch member being movable between open and closed positions, said catch in said open position being out of engagement with said slots, said catch in said closed position being disposed within said slots to prevent the movement of said side plates with respect to each other and prevent the opening of the door, the side plate carried by said door having a pivot pin, said latch member having an elongated

slot, said pivot pin extending through said slot, whereby said latch member may be rotated around said pivot pin and may also be moved vertically to a limited degree before or after such rotational movement, in order to permit the movement of said catch in a straight vertical direction in and out of said straight slots.

2. The structure described in claim 1, said latch member having a pair of sides which fit around and extend substantially parallel to the outer portions of said side plates when said latch member is in closed position, said catch extending transversely between and being formed integrally with said sides.

3. The structure described in claim 1, and an auxiliary latch rotatably mounted on said pivot pin, a pin carried by said latch member, said auxiliary latch being adapted to engage with said pin to hold said latch member in closed position.

4. The structure described in claim 3, said auxiliary latch having an elongated slot disposed around said pivot pin, whereby said auxiliary latch may be moved vertically to a limited degree for engagement and disengagement of said auxiliary latch with said pin.

5. An inside door lock comprising a pair of side plates adapted to be mounted in corresponding positions in the side edges of a door and door jamb, each of said side plates having an inner portion secured in overlying relationship to the door or door jamb by a fastening member which extends transversely to said side plate and door or door jamb, each of said side plates having an outer portion protruding from the door or door jamb, the outer portion of each of said side plates having a slot, said slots being aligned with each other when the door is closed, a latch member slidably and pivotally mounted on the outer portion of the side plate carried by the door, said latch member having a catch adapted to fit within said slots, said latch member being movable between open and closed positions, said catch in said open position being out of engagement with said slots, said catch in said closed position being disposed within said slots to prevent the movement of said side plates with respect to each other and prevent the opening of the door, and an auxiliary latch rotatably mounted on the same pivot means as said latch member, a pin carried by said latch member, said auxiliary latch being adapted upon rotation thereof to engage said pin to hold said latch member in closed position.

6. An inside door lock comprising a pair of side plates adapted to be mounted in corresponding positions on the side edges of a door and door jamb, each of said side plates having an inner portion secured in overlying relationship to the door or door jamb by a fastening member which extends transversely to said side plate and door or door jamb, each of said side plates having an outer portion protruding from the door or door jamb, the outer portion of each of said side plates having a vertically directed straight slot, said slots being aligned with each other when the door is closed, a latch member pivotally mounted on the outer portion of the side plate carried by the door, said latch member having a straight catch adapted to fit within said slots, said latch member being movable between open and closed positions, said catch in said open position being out of engagement with said slots, said catch in said closed position being disposed within said slots to prevent the movement of said side plates with respect to each other and prevent the opening of the door, said latch member having a pair of sides which fit around and extend substantially parallel to the outer portions of said side plates when said latch member is in closed position, said catch extending transversely between said sides, the side plate carried by said door having a pivot pin, each side of said latch member having an elongated slot, said pivot pin extending through one of said slots, whereby said latch member may be rotated around said pivot pin and may also move vertically to a limited degree to permit the movement of said catch in and out of said slots.

7. The structure described in claim 6, and an auxiliary latch rotatably mounted on said pivot pin, a pin carried by each side of said latch member, said auxiliary latch upon rotation thereof being adapted to engage one of said pins to hold said latch member in closed position.
